SIGNORS OF ONE-THIRD TO GEORGE MILLS BLACKSTONE, OF STAMFORD, LINCOLN,
ENGLAND.

INTERNAL-COMBUSTION ENGINE.

Application filed December 16, 1925, Serial No. 75,823, and in Great Britain November 25, 1924.

Our invention relates primarily to the combustion chambers of vertical internal combustion engines of the kind in which the air is compressed to high pressure and temperature sufficient to ignite the fuel which is sprayed into the compressed charge without the use of spraying air.

In connection with the injection of fuel into the compressed air in the above manner, the following considerations appear to us to be important.

When a jet of fuel leaves the nozzle it is comparatively cold. At some point in its path, however, it has acquired sufficient heat to begin to vapourize, and at a further point in its path it is completely vapourized. Each jet assumes a theoretically conical shape by the production of a surrounding fringe of vapour increasing in width along its path. The vapour fringe requires air to burn in over all its surface, but a supply of air adjacent the unvapourized jet is unproductive of any increment of power and tends merely to diminish the effectiveness of the force of the explosion.

The ideal explosion chamber determined solely in accordance with the above would appear to have a spherical wall opposite the jet nozzle and positioned at the region where the liquid fuel becomes completely vapourized, the area of the wall being determined by the necessity for providing a fringe of air outside the conical streams of vapour at the said region and the angle of spread of the jets. If the vapour jets of a multiple-orifice nozzle are arranged as closely as possible to the axis of the mean path (leaving however sufficient air between the vapour fringes for the latter to burn freely on their inner surfaces) the sphericity of the surface will tend to become more nearly plane; and in practice said wall can conveniently be made plane and its shape may conveniently be a regular polygon, i. e., if four jets are employed it may be square with the jets directed to points on the diagonals spaced inwardly from the angles of the square.

It is further generally desirable in internal combustion engines that the exhaust valve reciprocates vertically so as to facilitate lubrication and avoid distortion under

heat due to the weight of the head, and also that the port for said valve be formed in a plane surface, and the present invention has for its object to provide in vertical engines a form of cylinder head wherein the above considerations are suitably embodied or to a large extent reconciled by an effective compromise, having regard also to various difficulties requiring to be met in manufacture.

According to the invention the combustion chamber in such engines comprises a rectangular chamber having in one vertical wall a pocket or recess in the remote end of which is seated the injector nozzle, the rectangular base of the main portion of the combustion chamber co-operating with a turbulence block preferably comprising a rectangular extension on the piston top having small and generally rectangular parts cut away at two opposite corners in order to produce rapidly-moving columns of air adapted to set up turbulence within the compressed charge in the combustion chamber. The rectangular element of the combustion chamber preferably approximates to a cube with the addition of additional width in one horizontal dimension corresponding to the width of the aforesaid ports or cut away parts in the head of the turbulence block. This additional width may approximate to 20% increase over the other horizontal dimension, and is transverse to the mean path of the fuel.

The injector nozzle is adapted to inject preferably four pencils of fuel from the bottom of the recess across the rectangular chamber, the limiting orifices being directed generally towards the diagonals of the opposite wall which is also rectangular, and the cone of the recess being no larger than is necessary to give clearance to the said jets. The upper horizontal wall or roof of the combustion chamber is ported, and the exhaust valve reciprocates vertically in connection with the said port. The vertical wall of the rectangular combustion chamber situated opposite to the jets may be ported for the admission of air, the port being controlled by an inlet valve. Alternatively the said wall may be plain, the admission of air being controlled by a transfer valve in a

bifurcation of the passage leading from the port in the upper wall controlled by the vertically reciprocating valve.

The invention is illustrated in the accompanying drawings, in which:—

Fig. 1 shows a cross-section view of the cylinder head and valve mechanism.

Fig. 2 is a plan of a detail.

Fig. 3 is a crank shaft diagram.

10 Figs. 4 to 7 illustrate the movements of the cylinder and transfer valves, and

Fig. 8 is a modification of Fig. 2.

Referring to the drawings, the combustion chamber 1, as illustrated in Fig. 2 is 15 rectangular in plan and cooperates with a turbulence block 2 which is mounted on the piston 3 and is generally rectangular in plan, but has parts cut away at opposite corners, as illustrated at 4, in order to produce rapidly-moving columns of air adapted 20 to set up turbulence within the compressed charge in the combustion chamber. The dimensions of the block and the combustion chamber preferably approximate to 25 a cube having additional width in one horizontal dimension by an amount equal to the width of the cut away parts 4.

The fuel valve 5 is seated at the bottom of a recess 6 having a conical enlargement at its forward end formed in a vertical wall of the combustion chamber 1, and the exhaust valve 7 reciprocates vertically in a port 8 in the roof of the combustion chamber.

35 In the preferred form as shown in full lines in Fig. 1 the exhaust valve 7 serves also for an air inlet valve, the port 8 being opened to air and exhaust alternately by means of a transfer valve 9 seated behind 40 the cylinder valve 7. Alternatively, we may dispense with the transfer valve and provide a separate air inlet valve 10 as indicated in dotted lines in Fig. 1.

In the preferred form, the cylinder valve 45 7 is driven through a rocker by means of a cam 11 rotated by a shaft 12 moving at half engine speed and the transfer valve 9 is driven through a rocker by means of an eccentric 13 on the shaft 12.

50 In operation, assuming the piston is at the top of its compression stroke, the valves 7 and 9 will be in the position illustrated in Fig. 4, in which the port 8 is closed by the valve 7 and the valve 9 is in its central position. It should here be noted that the operative face of the valve 9 is slightly narrower than the common port 14, so that the valve in the said position admits of communication from the port 8 both to air inlet and to exhaust, the valve 9 being now moved upwardly so that the exhaust opening is in process of enlarging.

A charge is now fired and the piston moves down, the cylinder valve 7 beginning 65 to open when the piston is about 45 degrees

in front of the bottom dead centre (as indicated at IV in Fig. 3), by which time the valve 9 has moved upwardly approximately clear of the port 14 into the position shown in Fig. 5. Exhaust now commences and the valve 7 continues to open until it reaches the position shown in dotted lines in Fig. 5, which is approximately 45 degrees after bottom dead centre, and is indicated at V in Fig. 3. The valve 9 is now 75 moving downwardly, and when the piston reaches the top of the exhaust stroke, its position is as illustrated in Fig. 6, according to which the port 8 is open both to air and exhaust, owing to the relatively narrow face of the valve 9 compared with the opening of the port 14. By this arrangement any momentum that may be left in the exhaust gases will tend to draw in air from the air inlet and sweep out the passage between the ports 8 and 14. As the piston moves down, the exhaust is quickly closed by the valve 9, the points at which air is opened and exhaust is closed being indicated at A and B respectively in Fig. 3. The valve 7 has not yet been moved and remains open throughout the suction stroke till the piston reaches the bottom dead centre to which Fig. 7 corresponds, at which point the valve 7 has moved upwardly considerably as indicated, being finally closed at the point indicated at C in Fig. 3 early in the compression stroke.

It will thus be realized that in the form already described, the cylinder valve remains open for about 420 degrees of the crank shaft movement under the action of the cam 11. In the modification in which a separate air inlet valve 10 is employed, the cam 11 would require to be cut down by about 90 degrees on the cam shaft and the air inlet valve 10 could be operated by a cam similar to the modified cam 11.

It is to be understood that the dimensions of the free space in the combustion chamber, as illustrated in Fig. 1, are such that the outer fringes of the limiting jets of fuel are directed generally to the corners of the opposite wall of the combustion chamber and that the conicity of the forward part of the recess 6 is limited to giving the necessary clearance to these jets. The fuel valve nozzle is set back to such a distance as to permit of an efficient throw and spread of the fuel jets to ensure complete combustion without the deposit of liquid fuel on the opposite wall, a suitable angle of spread being 18° away from the mean axis of the nozzle. The turbulence ports 4 situated at opposite corners are so arranged as to secure the necessary turbulence without directing the air currents in such a manner that they will directly interfere with the normal throw of fuel from the jets, i. e., they will clear the fringes. It is, of course,

necessary that the total volume of the combustion chamber relatively to the diameter and stroke of the piston 3 are such as to ensure high compression of the charge necessary to produce efficient ignition of the fuel. In practice, with a combustion chamber shaped as described, the area of the rectangular part may be about one-quarter the area of the piston.

10 In the modification shown in plan in Fig. 8, the combustion chamber 1 is shaped as in Fig. 2, but the turbulence block 22 is circular and comes up through a circular hole 23 in a transverse web 24 formed at the bottom 15 of the combustion chamber. The circular block 22 is not ported, but holes 25 are formed in the web through which jets of air are forced by the piston to give the desired turbulence.

20 This modification is intended for use with an exhaust valve larger than that illustrated in Fig. 1 and larger in area than in the hole in the web 24 so that if the valve stem breaks, the head will not fall down into the 25 cylinder but will be caught by the web and thus avoid or minimize consequent damage.

Obviously the hole and turbulence block in this modification may take other shapes than circular.

30 Although we have illustrated the preferred form of the invention hitherto constructed, it will be realized that the particular dimensions of the throw and spread of the fuel may be varied in accordance, for 35 example, with the injector pressure and the pressure of air in the cylinder head.

I claim:—

1. In an internal combustion engine, a cylinder having its axis vertical, a rectangular combustion chamber at the top of said cylinder, the area of said chamber being considerably less than that of said cylinder, a piston, a turbulence block on said piston, said block being shaped to allow clearance for vertical turbulence jets between it and the wall of the combustion chamber, a recess in a vertical wall of said chamber, and a fuel delivery nozzle set back in said recess.

2. In an internal combustion engine, a cylinder having its axis vertical, a rectangular combustion chamber at the top of said cylinder, the area of said chamber being considerably less than that of said cylinder, a piston, a turbulence block on said piston, said block being shaped to allow clearance for vertical turbulence jets between it and the wall of the combustion chamber, a recess in a vertical wall of said chamber, and a fuel delivery nozzle set back in said recess, a port in the roof of said chamber for the exhaust of the combustion products.

3. In an internal combustion engine, a cylinder having its axis vertical, a rectangular combustion chamber at the top of said cylinder, the area of said chamber being consider-

ably less than that of said cylinder, a piston, a turbulence block on said piston, said block being shaped to allow clearance for vertical turbulence jets between it and the wall of the combustion chamber, a recess in a vertical wall of said chamber, a fuel delivery nozzle set back in said recess, a port in the roof of said chamber for the exhaust of the combustion products and for the inlet of air, a bifurcated passage leading from said port, and a transfer valve governing said bifurcation.

4. In an internal combustion engine, a cylinder having its axis vertical, a rectangular combustion chamber at the top of said cylinder, the area of said chamber being considerably less than that of said cylinder, a piston, a turbulence block on said piston, means whereby at the top of the stroke of said piston said chamber is only partially closed by said turbulence block so that turbulence jets are produced by the stroke of said piston, a recess in a vertical wall of said chamber, and a fuel delivery nozzle set back in said recess.

5. In an internal combustion engine, a cylinder having its axis vertical, a rectangular combustion chamber at the top of said cylinder, the area of said chamber being considerably less than that of said cylinder, a piston, a turbulence block on said piston, means whereby at the top of the stroke of said piston said chamber is only partially closed by said turbulence block so that turbulence jets are produced by the stroke of said piston, a recess in a vertical wall of said chamber, a fuel delivery nozzle set back in said recess, and a port in the roof of said chamber for the exhaust of the combustion products.

6. In an internal combustion engine, a cylinder having its axis vertical, a rectangular combustion chamber at the top of said cylinder, the area of said chamber being considerably less than that of said cylinder, a piston, a turbulence block on said piston, means whereby at the top of the stroke of said piston said chamber is only partially closed by said turbulence block so that turbulence jets are produced by the stroke of said piston, a recess in a vertical wall of said chamber, a fuel delivery nozzle set back in said recess, a port in the roof of said chamber for the exhaust of the combustion products and for the inlet of air, a bifurcated passage leading from said port, and a transfer valve governing said bifurcation.

7. In an internal combustion engine, a cylinder having its axis vertical, a rectangular combustion chamber at the top of said cylinder, the area of said chamber being considerably less than that of said cylinder, a piston, a turbulence block on said piston shaped generally to conform to the shape of said chamber but having cut away parts at opposite angles, a recess in a vertical wall of said chamber, and a fuel delivery nozzle set back in said recess.

8. In an internal combustion engine, a cylinder having its axis vertical, a rectangular combustion chamber at the top of said cylinder, the area of said chamber being considerably less than that of said cylinder, a piston, a turbulence block on said piston, shaped generally to conform to the shape of said chamber but having cut away parts at opposite angles, a recess in a vertical wall of said chamber, a fuel delivery nozzle set back in said recess, and a port in the roof of said chamber for the exhaust of the combustion products.
9. In an internal combustion engine, a cylinder having its axis vertical, a rectangular combustion chamber at the top of said cylinder, the area of said chamber being considerably less than that of said cylinder, a piston, a turbulence block on said piston, shaped generally to conform to the shape of said chamber but having cut away parts at opposite angles, a recess in a vertical wall of said chamber, a fuel delivery nozzle set back in said recess, a port in the roof of said chamber for the exhaust of the combustion products and for the inlet of air, a bifurcated passage leading from said port, and a transfer valve governing said bifurcation.
10. In an internal combustion engine, a cylinder, a combustion chamber, a piston, a turbulence block, the area of said chamber and block generally conforming and approximating to a rectangle having an appreciable difference in its major and minor dimensions, the block being cut away at opposite corners to a depth approximating the difference between the major and minor dimensions of the block.
11. In an internal combustion engine, a cylinder, a combustion chamber, a piston, a turbulence block, the area of said chamber and block generally conforming and approximating to a rectangle having an appreciable difference in its major and minor dimensions, the block being cut away at opposite corners to a depth approximating the difference between the major and minor dimensions of the block, the height of the combustion chamber corresponding to the minor dimension of the rectangular form of the chamber.
12. In an internal combustion engine, a cylinder having its axis vertical, a rectangular combustion chamber at the top of said cylinder, the area of said chamber being considerably less than that of said cylinder, a piston, a turbulence block on said piston, said block being shaped to allow clearance for vertical turbulence jets between it and the wall of the combustion chamber, a recess in a vertical wall of said chamber, a fuel delivery nozzle set back in said recess and having four divergent orifices directed to the diagonals of the free area of the opposite rectangular wall which is left uncovered by the turbulence block.

In testimony whereof we affix our signatures.

FRANK CARTER.
